UNITED STATES PATENT OFFICE.

ADOLPH GRAEFE, OF BROOKLYN, NEW YORK.

ADJUSTABLE STAND FOR FLOWER-POTS.

No. 811,712.

Specification of Letters Patent.

Patented Feb. 6, 1906.

Application filed July 26, 1905. Serial No. 271,168.

To all whom it may concern:

Be it known that I, ADOLPH GRAEFE, a citizen of the United States, and a resident of Brooklyn, in the county of Kings and State of New York, have invented certain new and useful Improvements in Adjustable Stands for Flower-Pots, of which the following is a specification.

This invention relates to that class of adjustable stands for flower-pots which are especially intended to be used for the arrangement and support of flower-pots and other articles for exhibition. Supports or stands of this character are designed to be adjusted vertically, so that the flower-pots and their contents can be maintained at the desired elevation.

The object of my invention is to provide a simple and improved adjustable stand or support of the class described which will be especially inexpensive in construction and which can be readily separated into "knock-down" condition for economy and conservation of space in transportation and packing.

A further object of my invention and improvements is to provide a stand or support of the class set forth which will possess advantages in points of convenience, ease of adjustment, durability, effectiveness, and positive operation and general efficiency.

In the drawings, Figure 1 is a perspective view of the stand or support embodying my improvements. Fig. 2 is a vertical transverse sectional view of the same. Figs. 3, 4, 5, and 6 are detail horizontal sectional views taken, respectively, on the lines *x x*, *y y*, *z z*, and *w w*, Fig. 2.

Corresponding parts in all the figures are denoted by the same reference characters.

My improved adjustable stand or support is preferably constructed in its entirety of metal.

Referring to the drawings, 1 designates a base member which is adapted to rest upon the floor and is provided centrally with a threaded cylindrical opening 2.

3 designates a tubular standard which is mounted vertically upon the base member 1 and is detachably connected therewith by means of a threaded cylindrical lower end 4, engaging with the threaded opening 2 of the base 1. The standard 3 preferably consists of a cylindrical tube, as shown.

5 designates a stem which is vertically adjustable longitudinally within the standard 3

and is received by and corresponds to the bore 6 of the standard 3, the stem 5 being in its greatest points of diameter preferably a little less than the diameter of the bore 6, so that the stem can move freely in its adjustable operation within the bore and will at the same time have no loose movement or undesirable extent of movement or play. The stem 5 operatively projects from the open top end 7 of the tubular standard 3 and is provided at its top end with a threaded cylindrical extension or projection, as at 8, which is received by a central cylindrical threaded opening 9 in a top table or platform member 10, whereby said member 10 is detachably connected with and mounted upon the stem 5. A circumferential shoulder, as at 11, is preferably provided upon the stem 5 just beneath the top threaded extension 8, upon which shoulder the top platform 10 can rest for purposes of greater security and strength.

The stem 5 is preferably of cylindrical shape and is provided with a longitudinal series of circumferential shoulders 12, spaced at short intervals or distances apart, which shoulders are adapted to be engaged by a tooth upon an adjustment-lever, hereinafter described, whereby the stem is retained in the position of vertical adjustment to which it has been moved. The surface of the stem 5 is preferably circumferentially tapered upwardly between the shoulders, as shown at 14, so that in the operation of moving the stem for a higher adjustment the shoulders 12 will slip past the tooth of the adjustment-lever, and when it is desired to lower the stem the tooth of the adjustment-lever is moved from contact with the shoulders 12, so that the stem can be slid downwardly within the tubular standard 3, a pawl-and-ratchet connection between the stem and its adjustment-supporting means being thus provided.

A special feature of my improvements is that the stem 5 being cylindrical and its shoulders being circumferential and the standard 3 having a cylindrical bore the stem 5, with the table or platform 10, which it carries, can be rotated or turned within the standard 3 at all times or points of its adjustable support, thus enabling convenient exhibition at all sides or points of the flowers which are supported by my improved stand or support.

The adjustment-lever 15 preferably com-

prises a yoke 16, the arms 17 17 of which are pivotally connected, as at 18, to the upper end of the tubular standard 3 at diametrically opposite sides, the yoke being extended 5 into an outwardly-projecting finger or thumb piece 19, by which the lever may be operated upon its fulcrum or pivot. Projecting inwardly from the lever 15, preferably at a point centrally between the yoke-arms 17, is 10 an extension 20, forming a tooth 21, which has a beveled end 22, adapted to engage under the shoulders 12 upon the adjustable stem 5, the plane of said bevel 22 being preferably such that it will present a flat horizontal surface corresponding to the under 15 surface of the shoulders 12 when the lever is at its lowermost point of rest, as shown in Fig. 2. It will be noted that the under surface 23 of the beveled end 22 will automatically slip past the shoulders 12, sliding over the tapered portion 14, when the stem 5 is drawn upwardly in the bore of the standard 3. The extension 20 and its tooth end 21 project into the bore 6 of the standard 3 and 20 project and operate in connection with the parts 12 and 14 of the stem 5 by means of an opening 24, formed in the wall of the tubular standard.

The detachable top table or platform 10 is 30 adapted to carry the flower-pot 25, as shown in Fig. 2, and for the purpose of a more secure rest or contact of the flower-pot upon said platform the latter is preferably provided with a radiating series of ribs, as at 26, 35 upon its top surface, which incline downwardly and toward the center, as at 27.

Under some circumstances the threaded connection between the top platform 10 and the stem 5 may be omitted, and the opening 40 9 of the platform 10 and the extension 8 of the stem 5 may be smooth and without threads, under which conditions the platform 10 will be supported upon the top shoulder 11 of the stem 5 and can be turned or rotated independent of any turning or rotating 45 movement of the stem 5.

The operation and advantages of my invention and improvements will be readily understood. The stand or support can be adjusted with a wide range vertically. To increase the vertical adjustment, it is only necessary to lift the stem 5 upwardly in the standard, when the adjustment-lever will automatically engage a shoulder of the stem at 55 the desired point of adjustment. To diminish the vertical adjustment, it is only necessary to withdraw the lever from engagement and push the stem downwardly in the standard until the desired point of adjustment is 60 reached, when the lever is released and engages one of the shoulders of the stem. At all points of vertical adjustment the parts immediately supporting the flower-pot can be turned or rotated to bring the flowers at 65 different points of view. The base, standard,

stem, and top table or platform can be conveniently and quickly separated or detached for purposes of packing or transportation.

Having thus described my invention, I claim and desire to secure by Letters Patent—

1. An adjustable support of the class described, comprising a base, a standard projecting from the base and having a cylindrical bore, a cylindrical stem adjustable within 75 said bore and having a series of circumferential shoulders or projections, means carried by the standard for engaging said shoulders, and a table or platform carried by the stem.

2. An adjustable support of the class described, comprising a base, a standard projecting therefrom and having a cylindrical bore, a cylindrical stem adjustable within said bore and having a series of circumferential shoulders or projections and a circumferential tapered or beveled surface intermediate between said shoulders and leading thereto, a pawl mechanism carried by the standard and projecting into operative engagement with said shoulders and tapered surface, and a table or platform carried by the stem. 85 90

3. An adjustable support of the class described, comprising a base, a tubular standard having a separable detachable connection with the base, a stem adjustable within 95 said detachable standard and separable therefrom, means carried by the standard for engaging the stem, and a table or platform separably and detachably connected to the 100 stem.

4. An adjustable support of the class described, comprising a base, a tubular cylindrical standard detachably connected with the base, a cylindrical stem adjustable in the 105 cylindrical bore of the tubular standard and separable from the latter, said stem having a circumferential series of projecting shoulders, means carried by the standard for engaging said shoulders, and a table or platform 110 detachably carried by the stem.

5. An adjustable support of the class described, comprising a base, a tubular cylindrical standard detachably connected with said base, a cylindrical stem adjustable in the 115 corresponding bore of the tubular standard and separable from the latter, said stem having a series of circumferential shoulders and a circumferential tapered or beveled surface intermediate between the shoulders and leading thereto, a pawl mechanism carried by the standard and operatively engaging said shoulders and tapered surface, and a table or platform 120 detachably carried by the stem.

6. An adjustable support of the class described, comprising a supporting-base, a standard projecting from the base and having a cylindrical bore, a revolving stem adjustable within said bore and having a vertical series of shoulders or projections cir- 125 130

cumferentially extending around said stem, means carried by the standard for engaging said cylindrical shoulders or projections at any point of the revolving movement of the 5 stem, and a table or platform carried by the stem.

7. An adjustable support of the class described, comprising a supporting-base, a standard having a cylindrical bore and a separable detachable connection with said base, a revolving stem adjustable within said bore and separable from the standard and having a vertical series of shoulders or projec-

tions circumferentially extending around said stem, means carried by the standard for engaging said cylindrical shoulders or projections at any point of the revolving movement of the 15 stem, and a table or platform separably and detachably connected to the stem.

In testimony whereof I have signed my 20 name in the presence of the subscribing witnesses.

ADOLPH GRAEFE.
